Primary Examiner — Darlington Ly

(57) **CLAIM**

The ornamental design for an electric motorcycle for kids, as shown and described.

DESCRIPTION

FIG. 1 is top, rear and left-side perspective view of an electric motorcycle for kids embodying my new design; FIG. 2 is bottom, front and left-side perspective view thereof;

FIG. 3 is a left-side elevation view thereof;

FIG. 4 is a right-side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged and partial perspective view of area 9 in FIG. 1.

The dot-dash broken lines do not form part of the claimed design and are provided for annotative purposes to show the area being enlarged.

1 Claim, 9 Drawing Sheets(56)
